UNITED STATES PATENT OFFICE.

HUBERT K. KRANTZ, OF WILKINSBURG, PENNSYLVANIA, ASSIGNOR TO WESTINGHOUSE ELECTRIC & MANUFACTURING COMPANY, A CORPORATION OF PENNSYLVANIA.

SWITCH MECHANISM.

Application filed April 18, 1922. Serial No. 555,140.

To all whom it may concern:

Be it known that I, HUBERT K. KRANTZ, a citizen of the United States, and a resident of Wilkinsburg, in the county of Allegheny and State of Pennsylvania, have invented a new and useful Improvement in Switch Mechanism, of which the following is a specification.

My invention relates to switch mechanism and particularly to switch mechanism of the safety enclosed type.

One object of my invention is to provide a simple positive interlocking mechanism between the door for the housing and the switch wherein predetermined movement of the switch and door are prevented by an interlocking member, and wherein the movement of the interlocking member is prevented except when the door and switch are in predetermined positions.

Another object of my invention is to provide a switch mechanism, having the above characteristics, wherein a latch mechanism serves to hold the door closed both at its free and at its hinged edges.

Another object of my invention is to provide an interlock mechanism for a safety switch wherein the interlocking bar is actuated by the latch for the door and wherein the switch is locked in open position by the latch before any opening movement of the door is permitted.

Another object of my invention is to provide an interlock mechanism of the above-designated character, wherein the interlocking bar is locked in switch-retaining position by the cover when the latter is out of any position other than closed position.

Another object of my invention is to provide a switch mechanism wherein the interlocking bar is slidably secured to the housing and wherein the operating mechanism therefor is carried by the movable cover.

A further object of my invention is to provide a switch interlock and door mechanism that is particularly well adapted for use with rotary switches having a snap action, such as switches of the type illustrated and described in the co-pending application Serial No. 420,047, filed October 27, 1920, by O. S. Jennings, and assigned to the Westinghouse Electric & Mfg. Company.

These and other objects, that will be made apparent throughout the further description of my invention, may be attained

by means of the switch mechanism herein-after described, and illustrated in the accompanying drawings, wherein:

Figure 1 is a front view of the switch mechanism, a portion of the cover being broken away to expose parts of the switch-interlock mechanism;

Fig. 2 is an elevational view of the switch mechanism illustrated in Fig. 1, showing a portion of the side of the cover and operating mechanism broken away;

Fig. 3 is a transverse section through the switch mechanism taken on the broken line III—III of Fig. 2, looking in the direction of the arrows;

Fig. 4 is a transverse section on the broken line IV—IV of Fig. 1, looking in the direction of the arrows;

Fig. 5 illustrates front, side and end elevations of a detail of the door latch mechanism;

Figs. 6 and 7 are front and end views, respectively, of a detail of the switch-interlock mechanism;

Figs. 8 and 9 are front and end views, respectively, of a detail of the door-latch mechanism; and

Figs. 10 and 11 are front and end views, respectively, of the interlocking bar.

Referring to the drawings, the apparatus includes a rectangular housing 12 that is made of sheet metal. The housing is provided with a sheet-metal cover 13 having a marginal strip 14 that fits over the side and end walls of the housing. The cover is provided with an arcuate portion 15 extending above the plane of the cover for the purpose of providing a space within which switch-blade members may operate when moved to open position. The cover is also provided with an opening 16 through which the usual fuse devices of the switch apparatus are accessible. This opening is closed by a movable door 17 that is secured thereto by means of hinges 18.

The main cover 13 is pivoted to the housing 12 by means of hinges 19 and is adapted to be locked in closed position by means of a pair of clips 21 and 22, the former being secured to the housing 12, while the latter is an integral part of a handle plate 23 that is secured to the side wall of the cover 13. The clips 21 and 22 are severally provided with perforations 24 that are aligned when the cover is in closed position and through

which the hasp of a lock may be inserted for locking the cover in closed position.

The handle plate 23 is provided with an opening 25 through which the fingers of the operator may be inserted for operating the cover, and a spring clip 26 is riveted to the plate and provided with a yielding projecting end 27 that is adapted to snap into a notch 28 in a plate 29 that is secured to the housing and which extends slightly beyond the edge thereof. The latch, comprising the clip 27 and the slot 28, serves to yieldingly retain the cover in closed position.

15 A switch panel of standard construction is mounted in the housing and comprises an insulating panel 31 upon which is mounted fuse clips 32, switch contact members 33 and switch pivot-jaw members 34. A 20 movable switch blade 35 is mounted in each of the switch pivot-jaw members 34, there being three in the switch mechanism illustrated herein. Each switch-blade member is provided with an insulating plate 36 having a notch 37 into which the switch-operating arm 38 is inserted.

The switch arm 38 is of standard construction consisting of a piece of round commercial bar bent to provide bearing portions 39 and 40 that are journaled in the side walls of the housing. The end 40 projects from the housing and is attached to a switch-operating mechanism 41 which may be of any preferred form, such, for instance, as that disclosed in the above-mentioned co-pending application.

45 A cam plate 42 is secured to the bar 38 by means of screws 43 and is moved with the switch. The cam consists of a flat metallic plate having its edge curved concentric with the axis of rotation of the switch arm. One end of the plate terminates adjacent the arcuate surface in a projecting finger 44, the purpose of which will hereinafter appear.

An interlocking bar 45, which consists of a flat metal plate bent in the shape of an angle bar, is slidably mounted upon the underside of the cover 13 and is secured thereto by means of rivets 46 that project through slots 47 in the interlocking bar 45.

The door 17 is provided with an inwardly-projecting cam plate 48 (see Figs. 1, 3 and 4) having a curved edge 49 concentric with the door hinges 18. One end 50 of the curved portion of the plate 48 terminates a short distance from the inner surface of the door 17. The flange α of the interlocking bar projects between the end of the plate 48 and the door 17. So long as the interlocking bar 45 is in the position illustrated in Figs. 1 and 4, opening movement of the door is prevented by reason of engagement of the bar 45 with the plate 48.

65 It will be seen that, when the interlock-

ing bar 45 is in the open position shown in Fig. 1, the right end thereof clears the cam plate 42 and permits opening and closing movement of the switch. The cam plate 42 prevents opening movement of the interlocking bar 45 to the right so long as the switch is in closed position and the cam plate 42 occupies the position illustrated in Figs. 1 and 2. The door 17, therefore, cannot be opened while the switch is in closed position and is retained in closed position until the bar 45 is moved to the right to the position indicated in dotted lines in Fig. 1.

When the switch is moved to open position, the cam plate 42 occupies the position indicated in dotted lines in Fig. 2, wherein the extension 44 lies clear of the inwardly-extending flange α of the interlocking bar 45. When the switch is open, the bar 45 may be moved to the right, in which position it extends across the path of movement of the cam plate 42 and prevents closing movement of switch. At this time, the left end of the bar 45 is withdrawn from the path of movement of the cam plate 48 on the door, and opening movement of the latter is permitted.

Referring to Fig. 4, it will be seen that, when the door is moved slightly out of closed position, the nose 50 of the cam plate 48 extends across the path of movement of the interlocking bar 45 and prevents releasing movement thereof. The bar, therefore, is held in interlocked position with the switch so long as the door is in open position and is in any position other than closed position. The cam plate 48 is provided with a stop projection 53 that engages the underside of the locking bar 45 and limits opening movement of the door.

The door 17 is provided with a latch bar 54 that is pivoted at 55 to the door. The latch is provided, at one end, with an inwardly-projecting cam plate 56 and, at the other end, with an inwardly-projecting finger 57 that is adapted to project into a notch 58 in the interlocking bar 45 when the door is in closed position or nearly closed position. The end of the latch bar 54, having the cam plate 56 thereon, is adapted to extend beneath the flange 59 of the cover 13 and, when in the position indicated in Fig. 1, serves to retain the door in closed position.

An operating handle 61 is secured to the latch bar and extends through a slot 62 in the cover. The latch bar is held in the position illustrated in full lines in Fig. 1 by means of a helical spring 63 that is secured, at one end, to the latch bar and, at the other end, to the housing by means of a rivet 64.

In order to open the door, the switch must first be moved to open position, where-in the cam plate 42 occupies the position il-

lustrated in dotted lines in Fig. 2. By reason of the clearance usually provided in constructions, such as the switch-operating mechanism illustrated in the above-referred 5 to co-pending application, provision is made on the locking bar to displace the extension 44 toward open position to insure proper operation of the switch-operating mechanism. The flange *b* of the locking bar 10 45 is therefore provided with an outwardly-turned cam portion 65 that is adapted to engage the extreme end of the extension 44 and move the switch mechanism toward open position when the interlocking bar 45 15 is actuated by the latch bar 54.

After the switch has been moved to open position, the bar 54 is turned in a clockwise direction by the handle 61 and moves the interlocking bar across the path of movement 20 of the cam plate 42, thus locking the switch in open position. This same movement withdraws the interlocking bar 45 from engagement with the cam plate 48 and permits opening movement of the door. Closing 25 movement of the actuating bar is prevented by the cam plate 48 in the manner previously described.

In order to close the switch, the door 17 must first be closed. When the door 17 is 30 moved to closed position, the inclined edge of the cam plate 56 on the latch bar 54 engages the flange 59 of the housing which automatically causes the latch to be rotated in a clockwise direction, thus bringing the 35 inwardly-projecting finger 57 of the latch bar 54 into registry with the notch 58 on the interlocking bar.

Final closing movement moves the finger 40 57 into the notch 58 wherein it is in position to move the interlocking bar to releasing position, or to the position illustrated in Fig. 1, when the door finally reaches closed 45 position. The free end of the latch bar 54 is drawn beneath the flange 59 of the cover 50 13 by the spring 53 after the door has moved to closed position. This latching movement moves the interlocking bar toward the left, thus permitting closing movement of the switch and preventing opening movement of the door.

In order to prevent access to the interior 55 of the housing, the latch bar 54 is provided with a threaded hole 66 that is aligned with the slot 62 in the door 17 and into which a screw may be inserted while the cover 13 is open for preventing releasing movement of the door latch bar 54. The switch-operating member 41 is provided with a flange portion 66 having a series of perforations 67 which are accessible when the switch is 60 in open position for receiving the hasp of a padlock which engages the bracket 68 and prevents closing movement of the switch.

It will be seen from the foregoing that 65 the door is doubly locked in closed position

when the switch is in closed position, and that the switch cannot be closed so long as the door is in open position or any position other than closed position. It is also apparent that the interlocking bar cannot 70 be moved except when the cover and switch are in predetermined positions. The construction is simple and positive in its action and relatively inexpensive to manufacture.

While I have illustrated and described but 75 one embodiment of my invention, it will be apparent to those skilled in the art that various changes, modifications, additions, substitutions and omissions may be made therein without departing from the spirit 80 and scope of my invention, as set forth in the appended claims.

I claim as my invention:

1. Switch mechanism comprising a housing, a movable switch member, a movable 85 door for the housing, a movable latch for the door, an interlock member actuated by the latch for releasably retaining the door in closed position and for preventing closing movement of the switch member when 90 inoperative to retain the door in closed position, and means actuated by the door for preventing releasing movement of the interlock member so long as the door is in other than closed position. 95

2. Switch mechanism comprising a housing, a movable switch member, a movable door for the housing, an interlock member for releasably retaining the door in closed 100 position and for preventing closing movement of the switch member when inoperative to retain the door in closed position, and means actuated by the door for preventing releasing movement of the interlock member 105 so long as the door is in other than fully closed position.

3. Switch mechanism comprising a housing, a movable switch member, a movable door for the housing, an interlock member 110 slidably mounted upon the housing for releasably retaining the door in closed position and for preventing closing movement of the switch member when inoperative to retain the door in closed position and means carried by the door for automatically moving the interlock member from interlocked 115 relation to the switch and for locking the door in closed position after the door has moved to substantially closed position.

4. Switch mechanism comprising a housing, a movable switch member, a movable door for the housing, an interlock member 120 movable independently of the door and switch member for alternately engaging the switch member and the door for retaining the door in closed position when the switch member is in operative position and for retaining the switch member in inoperative position when the door is open and means 125 including separate means on the door and 130

switch member for preventing movement of the interlock member except when the door and switch are in predetermined positions.

5. Switch mechanism comprising a housing, a movable switch member, a movable door for the housing, an interlock member movably mounted on the housing for alternately preventing predetermined movements of the door and switch member and a latch carried by the door for operatively engaging the interlock member when the door is in closed position and for moving the interlocking member into interlocked relation to the switch during the releasing movement of the latch.

6. Switch mechanism comprising a housing, a movable switch member, a movable door for the housing, an interlock member movably mounted on the housing for alternately preventing predetermined movements of the door and switch member, a latch carried by the door and means actuated by the closing movement of the door for moving the latch into operative engagement with the interlock member. 20

In testimony whereof, I have hereunto subscribed my name this 17th day of April 1922. 25

HUBERT K. KRANTZ.
